UNITED STATES PATENT OFFICE.

JOHN F. O'CONNOR, OF CHICAGO, ILLINOIS, ASSIGNEE TO WILLIAM H. MINER, OF CHAZY, NEW YORK.

DRAFT-GEAR FOR LOCOMOTIVES.

1,250,493.

Specification of Letters Patent. Patented Dec. 18, 1917.

Application filed October 18, 1915. Serial No. 56,429.

To all whom it may concern:

Be it known that I, JOHN F. O'CONNOR, a citizen of the United States, residing at Chicago, in the county of Cook and State 5 of Illinois, have invented a certain new and useful Improvement in Draft-Gears for Locomotives, of which the following is a full, clear, concise, and exact description, reference being had to the accompanying drawings, forming a part of this specification.

This invention relates to improvements in draft gears for locomotives.

The object of the invention is to provide a draft gear of very high capacity which is particularly adapted for use on the front ends of locomotives where the same are required to be confined in a relatively small space.

In the drawing forming a part of this specification, Figure 1 is a horizontal, sectional view of a draft gear embodying my improvements, parts of the locomotive frame being shown in section. Fig. 2 is a longitudinal, vertical sectional view taken substantially on the lines 2—2 of Fig. 1. Figs 3 and 4 are transverse, sectional views taken on the lines 3—3 and 4—4, respectively, of Fig. 2. Fig. 5 is a detail elevation of one of the wedges with its extension.

In said drawing, 10 denotes the portion of the locomotive frame at the forward end thereof, the same being provided with a substantially rectangular pocket 11 within which is mounted the improved gear.

As shown, the gear comprises a casting 12 having a pair of friction cylinders 13 cast integrally therewith, said cylinders being spaced apart and on opposite sides of the casting 12. Each of the friction cylinders 13 merges with a spring casing 14 at the rear thereof, each of the spring casings 14 having an integral rear wall 15, said walls 15 being perforated to receive therethrough extensions 16 in the form of bolts which are formed integrally with wedges 17 of the friction mechanisms. At the rear of the walls or partitions 15, is provided a transversely extending chamber within which is slidably mounted an evener or equalizer 18, the latter being perforated and receiving through the perforations the rear or inner ends of the bolts 16 on which are carried the retaining nuts 19—19. Coöoperating with each of the friction cylinders 13 are friction shoes 20 and a wedge 17, there being a plu-

rality of anti-friction rollers 21 interposed between each wedge and the coöperating set of friction shoes. At the rear of each set of friction shoes within each spring casing 14 and surrounding the bolts or wedge extensions 16, is a heavy spring 22.

The parallel friction shells and spring casings are spaced sufficiently to permit the rear end of the draw-bar 23 to pass therebetween, the inner end of the draw-bar 23 abutting a hollow forward extension 24 formed centrally on the equalizer 18, said extension 24 being confined between the inner walls of the friction casings. A U-shaped short yoke 25 straddles the rear end 70 of the casting 12 and is connected to the inner end of the draw-bar 23 by means of a vertically extending key 26, the latter being slideable rearwardly in elongated slots 27 formed in the upper and lower arms of 75 the yoke 25. The key 26 is adapted to be inserted through an upper opening 28 in the frame work of the locomotive and the lower end of the key 26 is slideable in a similar lower opening 29. In normal position of the 80 parts, the front face of the extension 24 engages two vertical, removable keys or stops 30—30 which extend through the upper and lower walls of the locomotive casting 10 and thereby prevent the equalizer 18 from being 85 moved forwardly. Each of the vertically extending keys 30 is also preferably beveled on its inner face as indicated at 31 to thereby accommodate radial movements of the draw-bar 23.

The operation is as follows: Upon inward movement of the draw-bar the main casting 12 is prevented from rearward movement by its engagement with the rear wall 32 of the locomotive casting 10 and, as the 90 equalizer 18 is moved rearwardly, the bolts 16 or wedge extensions are also moved rearwardly, thus pulling the wedges 17 and friction shoes 20 rearwardly against the action of the springs 22, the shock being thus absorbed by two sets of friction mechanisms. Under draft, the equalizer 18 being held stationary by the keys 30, the forward movement of the yoke 25 will pull the main casting 12 forwardly and hence the friction 100 shells 13 will slide relatively to the friction shoes and friction will be created due to the gradual compression of the springs 22. The amount of compression under buff is limited by engagement of the equalizer 18 110

with the rear wall 32 and, under draft, by engagement of the yoke with the equalizer 18.

From the preceding description, it will be seen that the gear which I have provided is of very high capacity and on account of the arrangement of shells and casings I am enabled to mount the rear end of the draw-bar between the friction mechanisms, thereby providing a gear of very short length on its center line.

Various changes and modifications may be made in the details of construction and arrangement of the parts without departing from the spirit of the invention, and I contemplate all such changes and modifications as come within the scope of the claims appended hereto. In this connection it will of course, be obvious that the gear is adapted for other use than merely on locomotives.

I claim:

1. In a device of the character described, the combination with spaced parallelly arranged friction shells, friction devices operable therewith at the front ends thereof, springs at the rear of said friction devices, of an equalizer actuated by the draw-bar in buff, connections between said equalizer and the friction devices, and means located between the friction shells for preventing forward movement of the equalizer.

2. In a device of the character described, the combination with spaced friction shells adapted to have a draw-bar extend therebetween, of an equalizer with which the draw-bar is adapted to directly engage and

operate under buff, friction elements and springs within each of said shells, said shells being prevented from rearward movement under buff, the friction elements being moved rearwardly simultaneously by said equalizer upon rearward movement of the draw-bar.

3. In a device of the character described, the combination with spaced parallelly arranged friction shells, friction devices operable therewith at the front ends thereof, springs at the rear of said friction devices, of an equalizer actuated by the draw-bar in buff, and connections between said equalizer and the friction devices, said equalizer remaining stationary under draft and the friction shells being forwardly movable with the draw-bar.

4. In a device of the character described, the combination with a car structure having a pocket therein, of a casting slidably mounted in said pocket, said casting having formed integrally therewith a pair of spaced, combined friction shell and spring casings, friction elements and springs within each of said casings, said friction elements including a wedge having a rearward extension, means connecting said extensions whereby the latter are operated simultaneously, and a draw-bar for operating said means.

In witness that I claim the foregoing I have hereunto subscribed my name this 4th day of October, 1915.

JOHN F. O'CONNOR.
